CLAIM

The ornamental design for a corner shelf, as shown and described.

DESCRIPTION

FIG. 1 is a front, top perspective view of a corner shelf, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the corner shelf, shown in a position of use; and,

FIG. 10 is another perspective view of the corner shelf, shown in a position of use.

The broken lines are shown for the purpose of illustrating both parts of the corner shelf as well as environmental subject matter. None of the broken lines form part of the claimed design.

1 Claim, 10 Drawing Sheets(56)
